CLAMP

Zelmer E. Snow, Arvada, Colo.

Application May 7, 1947, Serial No. 746,497

4 Claims. (Cl. 24—243)

1

This invention relates to a clamp of extremely simple construction and which is adapted for use for detachably clamping mesh wire, wire strands or any other material to be stretched and which is especially constructed and arranged to enable the clamp to be quickly and easily attached to or detached from an end of a strip, strand or strands to be stretched.

More particularly, it is an object of the invention to provide a clamp which is very durable and which is composed of few parts capable of being readily assembled or disassembled for attaching or detaching the clamp and which may be readily moved to an operative or clamping position for effectively holding an element or elements disposed between the jaws thereof.

Still a further object of the invention is to provide a clamp having means for exerting a substantially uniform pressure throughout the entire length thereof upon an element or elements disposed between the jaws of the clamp.

Still another object of the invention is to provide a clamp having means for effectively latching it in a clamping position to prevent accidental disengagement thereof.

Various other objects and advantages of the invention will hereinafter become more fully apparent from the following description of the drawings, illustrating a preferred embodiment of the invention, and wherein:

Figure 1 is a side elevational view showing the clamp in an operative position and in engagement with a portion of a strip of mesh wire fabric;

Figure 2 is a view taken at right angles to Figure 1 and showing the clamp in an operative position and attached to a draw bar of a stretching mechanism, not shown; and

Figures 3 and 4 are cross sectional views taken substantially along planes as indicated by the lines 3—3 and 4—4, respectively, of Figure 1.

Referring more particularly to the drawing, the improved clamp in its entirety is designated generally 5 and includes two elongated bars 6, 7 which combine to form the two clamping jaws of the clamp 5.

A rod or strand of heavy gauge wire 8 extends along the outer edge of the bar 6, and is fastened thereto, in any suitable manner, as by means of staples 9, and is preferably located in a longitudinally disposed groove or channel 10 of said bar 6, as best seen in Figure 3. The ends of the rod or strand 8 extend beyond the ends of the bar 6 and terminate in hooks 11 which open outwardly of said bar 6 and which are disposed

beyond the ends thereof, for a purpose which will hereinafter become apparent.

The other clamping bar or jaw 7 is provided, intermediate of its ends, with a pair of ears 12, which are preferably secured in recesses 13 of the sides thereof by one or more fastenings 14, said ears 12 extending to beyond the outer side of the bar 7 and being provided with a pin 15 which extends between the outer portions thereof and which forms a pivot for the headed end of a lever 16. The head 17 of the lever 16 is provided with an arcuate edge 18 which is eccentrically disposed relatively to the pivot 15, for a purpose which will hereinafter become apparent. The pivot pin 15 carries bushings or spacing sleeves 19 which are disposed thereon between the ears 12 and the head 17 for retaining said head in spaced relationship to the ears, for a purpose which will hereinafter become apparent.

The bar or jaw 7 has screw eyes 20 projecting from its outer side, the openings of which are disposed transversely of said bar 7, for loosely receiving and guiding chains 21 and 22 which extend therethrough. The remote ends of the chains 21 and 22 detachably engage over the hooks 11 and said chains are provided with elongated links 23 and 24, at their opposite, adjacent ends which loosely engage openings 25 and 26, respectively, in the head 17 and which are located on opposite sides of and spaced from the pivot 15, and by which the chains are pivotally connected to the head 17.

The lever 16 has a hook 27 pivotally connected at its shank end thereto and intermediate of the ends thereof and which is disposed to swing in a plane substantially parallel to the plane of the lever 16 and which normally extends from the inner edge of said lever.

The drawing illustrates the clamp 5 in an operative positive and with an end portion of a strip of mesh wire fabric or the like 28, shown clamped between the bars or jaws 6 and 7 thereof. With the clamp 5 thus disposed, the remote ends of the chains 21 and 22 engage the hooks 11 and the lever 16 is swung downwardly with respect to the clamp jaws and disposed substantially parallel thereto, so that the adjacent ends of the chains 21 and 22 are drawn toward one another and so that the portion of the edge 18 of the lever head 17, which is most remote to the pivot 15, is in engagement with the outer side of the jaw or bar 7, so that said portion will combine with the chains for retaining the jaws or bars in adjacent, clamping relationship. It will be readily apparent that the chains 21 and 22

will engage around the outer ends of the bar 7 to combine with the hooks 11 and the cam edge 18 for holding the jaws or bars in clamping relationship, adjacent their ends and intermediate thereof, and the outer edges and ends of the bar 7 are preferably covered with reinforcing strips of metal or the like, as seen at 29, to prevent the chains 21 and 22 from cutting into the ends of the bar or jaw 7. When the lever 16 is thus disposed, as seen in Figure 1, the hook 27 is engaged with the lowermost eye 20, for detachably latching the lever 16 in an operative position and for preventing accidental release thereof.

To release the clamp 5 from the wire fabric strip 28, the free end of the lever 16 is swung inwardly or toward the jaws 6 and 7, sufficiently to disengage the hook 27, after which said lever is swung outwardly or in a counterclockwise direction for releasing the pull on the chains 21 and 22 and for moving the eccentric edge 18 away from the jaw or bar 7. The remote ends of the chains 21 and 22 can then be disengaged from the hooks 11 for disengaging the jaws or bars 6 and 7, thereby releasing the strip 28. It will be readily apparent that the clamp 5 may be utilized for clamping one or a plurality of strands of wire, not shown, or any other element to be stretched or pulled.

The clamp 5 is adapted to be attached to any conventional stretching mechanism, not shown, and may be utilized in conjunction with a draw bar 30, of such mechanism and which is provided with flexible members 31, such as chains which are anchored thereto, at corresponding ends thereof and which are provided with hooks 32 at their free ends. The chains 31 are adapted to engage around the clamping jaws or bars 6 and 7, adjacent the ends thereof, and with the hooks 32 engaged with links of the chains for detachably connecting the clamp 5 to the drawbar 30 and after the clamp 5 has been applied to the element to be stretched or pulled. Likewise, it

will be readily apparent that the chains 31 may be disconnected from the clamp jaws before the release thereof.

Various modifications and changes are contemplated and may obviously be resorted to, without departing from the spirit or scope of the invention as hereinafter defined by the appended claims.

I claim as my invention:

- 10 1. In a clamp of the character described, a pair of elongated bars forming clamping jaws, one of said bars being provided with a hook disposed beyond each end thereof, a lever having one end pivotally supported on the other bar and outwardly of the outer side thereof and a pair of flexible members having remote ends detachably connected to said hooks and engaging slidably over the outer end corners of the last mentioned bar or jaw and having opposite adjacent ends pivotally connected to the lever on opposite sides of and spaced from the lever pivot whereby said flexible members will be tightened when the lever is swung in one direction relatively to the jaws for drawing the jaws together and into clamping relationship.
- 15 2. A clamp as in claim 1, said lever having an eccentrically disposed cam edge at its inner end disposed in engagement with the outer side of the last mentioned bar or jaw when the jaws are disposed in clamping position.
- 20 3. A clamp as in claim 1, and means for detachably latching the lever in an operative position relatively to the jaws.
- 25 4. A clamp as in claim 1, said last mentioned bar or jaw having eyes projecting from the outer side thereof and forming guides for said flexible members, and a hook carried by said lever for detachably engaging one of said eyes for releasably retaining the lever in an operative position.
